Norman G. Wintermantel, Palos Heights, Ill., assignor to
American Machine and Foundry Company, a corpora-
tion of New Jersey

Original application February 28, 1956, Serial No. 40,402,
now Design Patent No. 181,116, dated October 1, 1957.
Divided and this application January 4, 1957, Serial
No. 44,394

Term of patent 14 years

(Cl. D90—5)

Fig. 1 is a side elevation of a combined cycle mud guard and shield therefor showing my new design, the opposite side being substantially like the side shown.

Fig. 2 is a sectional view of the cycle mud guard and shield therefor taken on the line 2—2 of Fig. 1, looking in the direction of the arrows; and

Fig. 3 is a top plan view of Fig. 1.

The broken lines in Fig. 1 are for illustrative purposes only.

This application is a division of my design application S.N. 40,402 filed February 28, 1956, now Patent D. 181,116.

I claim:

The ornamental design for a combined cycle mud guard and shield therefor, as shown and described.
